UNITED STATES PATENT OFFICE

HENRY J. GAISMAN, OF NEW YORK, N. Y., ASSIGNOR TO GILLETTE SAFETY RAZOR COMPANY, OF BOSTON, MASSACHUSETTS, A CORPORATION OF DELAWARE

SAFETY RAZOR

Application filed April 17, 1931. Serial No. 530,837.

The object of my invention is to provide a safety razor in which blade clamping members are movably retained together and in which said members may be moved to different positions relative to a handle attached thereto, the means that retain the blade clamped for shaving also serving to retain the clamping means and the blade in shaving position with relation to the handle.

10 In carrying out my invention I provide blade clamping members including a guard and a cap or blade backing, pivotally connected together, a handle attached to the guard member, and means operative within 15 the handle to engage the cap or backing member to retain the latter clamped against the blade, whereby when said means are released from the cap the latter may be swung away from the blade for removal and replacement.

20 My invention also comprises novel details of improvement that will be more fully hereinafter set forth and then pointed out in the claims.

25 In the accompanying drawing—

Fig. 1 is a side elevation of a portion of a 30 razor embodying my invention, with the parts in shaving position;

Fig. 2 is a cross section on line 2, 2 in Figure 3;

Fig. 3 is a cross section on line 3, 3 in Figure 1;

Fig. 4 is a view similar to Figure 3 showing the cap or backing member in released position;

Fig. 5 is a plan view showing the parts spread for removal or applying a blade, and

Fig. 6 is a side view showing the parts in position for storage.

Similar numerals indicate corresponding 40 parts in the several views.

The numeral 1 indicates a guard member, which may be, generally, of any desired construction, and at 2 is a cap or blade backing member, a blade 3 being adapted to be clamped between said members in shaving position. The members 1 and 2 are pivotally connected at adjacent ends as by means of a pivot 4 carried by one of said members, such as the guard member, and operative in a slot 5 in the other member, such as the cap 2, 45

whereby said members may have relative lateral movement for clamping the blade between them. The cap or backing member 2 is shown provided with projecting means at 6 adapted to enter a suitable aperture 7 in the blade to position the latter with relation to the guard and the cap. The guard member 1 is shown provided with a longitudinal groove 8 to receive the projecting means 6. At 9 is a handle, shown pivotally connected with the guard member 1, for which purpose said member is shown provided with spaced ears, between which the adjacent end of the handle is fitted and pivotally attached thereto by means of pivots 11, shown in the form of screws having circular bearing portions 12 journaled in bearing holes 13 in the ears 10, the screws being attached to the handle, whereby the handle and the guard are pivotally connected so that the guard may be set 70 in shaving position with respect to the handle, as shown in Figure 3, or may be turned to a position substantially parallel to the handle, as for storage, as shown in Figure 6.

For clamping the blade between the members 1 and 2 I provided a rod 14 that is 75 slideable in a longitudinal bore 15 in the handle 9 and between the screws or pivots 11, and through an opening 17a in the guard member 1. The rod 14, at its outer end, is shown provided with screw threads at 16 adapted to

mesh with the threaded bore 17 in the cap or clamping member 2, as illustrated in Figures 2 and 3. When the rod 14 is released from member 2 the latter may be swung on its 80 pivot 4 away from the guard member to permit removal and replacement of a blade.

By preference I provided a spring 18 cooperative with the handle 9 and with rod 14 normally tending to move the rod in a direction 85 away from the cap member 2. Rod 14 is shown provided with a stop or shoulder 19 slidably in an enlarged portion 15a on the bore 15, the spring 18 bearing against said stop and against an abutting stop portion 9a 90 of the handle. The normal expansion of the spring 18 tends to move the rod 14 outwardly to withdraw the rod from the cap member, as illustrated in Fig. 4. The rod

14 is also shown provided with a stop shoul- 95 100

der 20, (Fig. 2), which is adapted to engage a plug 21 shown secured by threads at the outer end of the bore of handle 9. A fingerpiece 22 secured at the outer end of rod 14 permits manipulation of said rod, and is adapted to abut against the end of the handle when the parts are in shaving position, as in Fig. 2.

To apply a blade the members 1 and 2 are 10 swung apart, as illustrated in Fig. 5, a blade 3 may be placed upon the cap or backing member 2 and positioned thereon, the projecting means 6 entering the aperture 7 of the blade, and then the members 1 and 2 are 15 swung together with the blade therebetween, the rod 14 being normally retracted from the backing member, as in Fig. 4. The rod 14 will next be pushed inwardly, against the tension of the spring, to engage the threads 16 in the threaded aperture 17 of the cap member, and by rotating the rod the cap member will be drawn toward the guard member to clamp the blade between said members, the 20 pivot 4 and slot 5 permitting lateral movement of said members for the clamping purpose, as in Fig. 3. The spring 18 will be compressed between the stops 9a and 19 and will serve to resiliently assist the clamping of the guard and cap members against the blade. 25 Although the handle is pivoted to the guard member, the rod 14, being slidably guided in the handle, will engage the cap member, as in Fig. 3, and the blade holder, comprising the members 1 and 2, will be retained by the rod substantially at a right angle with respect to the handle in shaving position. When the rod 14 is released from the cap member, (Fig. 4), the latter may be swung away from the guard member around the pivot 4, as in dotted lines in Fig. 6, for removal and replacement of a blade, and the blade holder may be 30 swung on its pivots 11 to a position substantially parallel to and one side of the handle to reduce the width of the razor for storage 35 and the like.

Having now described my invention what I claim is:

1. A safety razor comprising blade clamping members, a handle pivotally connected 50 with one of said members and adapted to be folded thereagainst, a rod slidably along said handle, said rod and the other member having cooperative means to clamp said members against a blade, and means cooperative 55 between said members to permit them to move toward one another while being clamped against the blade.

2. A safety razor comprising blade clamping members, a handle pivotally connected 60 with one of said members and adapted to be folded thereagainst, a rod slidably along said handle and provided with a threaded end portion, the other member having a threaded opening to receive the threaded end of the 65 rod, whereby the members may be clamped

against the blade, and means pivotally connecting said members at adjacent ends to permit said members to have movement toward one another while clamping a blade therebetween.

3. A safety razor comprising a guard member and a blade backing member, the guard member having spaced ears, a handle having a portion between said ears and pivotally attached thereto, said handle having a longitudinal bore extending between said ears, and a rod slidable in said bore and through an opening in the guard member, said rod and backing member having cooperative means for clamping the backing member against a 80 blade.

4. A safety razor as set forth in claim 3 provided with a spring within said bore and operative against the handle, the rod having a stop operative with the spring, whereby the latter tends to push the rod in a direction away from the backing member and with relation to the guard member to permit the latter to rotate relatively to the handle.

HENRY J. GAISMAN.
